(57) **CLAIM**

The ornamental design of a wearable electronic device, as shown and described.

DESCRIPTION

FIG. 1 is a perspective view of a wearable electronic device in accordance with the present invention;

FIG. 2 is another perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The features shown in broken lines in the various Figures are for illustrating environmental structure and form no part of the claimed design. The surfaces of the wearable electronic device are not limited to any color designations.

Generally, the invention pertains to an ornamental design for an article of manufacture. The article is not limited to the scale shown herein. As indicated in the title, the article of manufacture to which the ornamental design has been applied is a wearable electronic device, media player (e.g., music, video and/or game player), media storage device, a voice-controlled assistant, an augmented reality (AR) display, a virtual reality (VR) display, a communication device, a novelty item or toy.
